TENSION MEANS FOR WARP BEAMS AND THE LIKE

Application filed April 14, 1930. Serial No. 444,298.

This invention relates to the weaving art and is more particularly concerned with means for applying uniform tension to the threads of the warp as they are drawn off the warp beam by the take up.

The weight tautened chains and ropes which are at present used to apply frictional warp tensioning drag on the heads of the warp beams frequently "hang" or stick, resulting in uneven weaving producing thick and thin spots in the weave with resulting defects making the woven piece a "second" and necessitating its sale as such at a financial loss.

The positive gear-driven automatic let-off mechanism of the well known Roper and Bradley types also used at present for the lower warp beams of Terry looms, for example, are relatively expensive equipment, requiring many additional parts, and reducing the number of looms than can be cared for by one loom "fixer".

It has also been proposed to use a flexible strap, chain or brake band engaging a braking drum on the warp beam head and anchored to the loom frame, the strap, chain or brake band applying a pre-adjusted constant frictional braking tension to the drum. These arrangements have not been successful in use since the spindles on the warp beam heads which journal in trunnions in the loom frame are frequently "out of round" and are often bent by the handling of the heavy warp beams in the slashing room. The result is that with the spindles off centre in their journals the warp threads will let off with alternating increased and decreased speed producing uneven weaving with thick and thin spots and ridges. With the frictional drag or tension producing straps, chains or brake bands anchored to the frame and under constant braking tension, this uneven movement of the warp beam roll will with the reduced rate of turning movement of an off centre roll, produce such a heavy tension on the warp threads as they are drawn by the constant pull of the take up, as frequently to cause breakage as well as uneven weaving giving a decreased value to the product and causing financial loss to the manufacturer.

In accordance with the present invention I have provided a constant even braking tension on the warp beam irrespective of the trueness or out of round condition of the beam journaling spindles so that an even tension is exerted on the warp at all times and the relatively expensive automatic let-off positive gear drive is unnecessary.

A feature of the present invention consists of a brake band mounted on the loom frame against rotatory movement with or relatively to the braking drum of the warp beam which it encircles and frictionally engages and coincidentally movable bodily with the warp beam and its drum while maintaining constant frictional drag thereon, in response to bodily movement of the warp beam caused by out of round or bent journaling spindles. Such a tension-producing brake band may be, and preferably is, applied to both heads of the warp beams and particularly to the wider beams so that uniform tension may be secured under all conditions.

As a supplemental feature, the invention includes a brake band structure comprising inherently rigid, arcuate band sections having hingedly connected confronting ends of a particularly advantageous construction permitting quick release of the band for drawing back the warp, and interconnected tension adjusting ends, one of said band sections having a radial extension guided in a slotted extension of the frame for bodily movement of the brake band with the warp beam under off centre or bent conditions of its bearing spindles and held by said slotted extension against rotatory movement with the warp beam. Thus the brake band, being adjusted to a predetermined frictional drag on the beam head drum "floats" with the beam as it rises or drops bodily through off centre or bent journaling spindles and applies the same uniform tension producing frictional drag under all conditions.

As a further feature of the invention I have provided a drum mounting a brake band as above described and adapted to be applied as an attachment to the spindles of warp beam heads, such for example, as the gear driven Roper or Bartlett type or the chain embraced

type, thus adapting the invention, without modification of existing structure to all types of warp beams. In connection with this attachment I have provided a ratchet wheel for attachment to the shaft, and pawls carried by the drum to cooperate therewith, provided with externally operable quick release or throw-out means for the pawls facilitating application and removal of the warp beams from the end drums.

These and other features and advantages of the invention will be more clearly apparent from the following detailed description which is to be read in conjunction with the accompanying drawings forming part thereof in which:

Figure 1 is a perspective view of a portion of a standard loom with my warp beam tensioning means applied thereto,

Figure 2 is a view in side elevation of the beam head, drum and band brake shown in Figure 1,

Figure 3 is an enlarged transverse vertical section taken on line 3—3 of Figure 2,

Figure 4 is a perspective detail of the brake guiding and restraining bracket,

Figure 5 is a front elevation of a separate drum and brake attachment,

Figure 6 is a vertical section on line 6—6 of Figure 5,

Figures 7, 8 and 9 are details of the pawl and ratchet mechanism.

In the drawings, Figure 1, the lower warp beam 1 of a standard type Terry loom shown, is provided with the usual heads 2, of which one, only, is shown having axial spindles 3 outstanding therefrom and journaling in bearings 4 on the loom frame 5, with a spacing sleeve or collar 6 interposed between head and bearing.

One or both of the beam heads 2 may be provided on its outer face with a smooth faced friction drum 7, concentric with the axis of the head and beam and which may be cast integral with the head and connected with its hub 2^a by radial webs 8 as shown in Figure 1. The peripheral face 9 of the friction drum may be provided, if desired, with edge flanges 10, as shown in Figure 3.

In accordance with my present invention I provide a band brake shaped to said drum and embracing and engaging the peripheral face with constant frictional braking pressure, adjustably variable. This band brake is formed of two complementary inherently rigid arcuate metal sections 11 and 12, which may, for example, be castings. The under-face of each section may and preferably is, lined with a facing strip 13 of leather or other

suitable friction material, appropriately held thereto. These sections are arranged on the drum with confronting upper ends and with these ends hingedly linked so as to provide a fixed relative position of these ends in pressure applying position, and a released

determinate and relatively moved position releasing pressure on the drum.

Accordingly, the upper end of band section 12 is formed with an enlarged head 14 having a transverse bore 15 therein. The adjacent end of band section 11 is formed with a similar and larger head 16 having a central passageway 17 (Figs. 1 and 3) and a transverse bore 18 of large diameter in which is journaled a cylindrical plug 19 having a bore 20 extending therethrough parallel to its longitudinal axis and offset from the center thereof as shown in Figure 3. A hinging link 21 has its opposite ends inturned, as at 22, Figure 3, and inserted in the bores 15 and 20 of the heads 14 and 16, respectively, thus hingedly connecting the sections 12, 11. The inner end of a plug rotating rod 23 occupies the passageway 17 of head 16 and is threaded into a radial socket 24 (Figure 3) in the intermediate portion of the plug 19 positioned so that when the rod 23 is drawn down to rest upon the face of band section 11, as shown in Figures 1 and 2, the link 21 will be positioned on the dead center, with the band section 12 drawn toward section 11, contracting the band on the drum. Movement of the rod 23 upwardly from this position will expand the band and release its clamping pressure on the drum.

This is true because the confronting lower ends of the band sections 11 and 12 remain connected. As shown in Figures 1 and 2, the lower end of band section 12 terminates short of the vertical radius of the drum 7 and is provided with a short outwardly offset foot 25 having a bore transversely therethrough. The lower end of the complementary band section 11 at a point in the vertical diameter of the drum, is provided with a corresponding outwardly offset foot portion 26 having an alined transverse bore therein, and with an elongated rigid integral flattened extension 27 alining therewith and depending in a line radial to the axis of rotation of the drum 7, beam head 2, and warp beam 1; as shown, alined with the vertical diameter thereof. The shank of a connecting bolt 28 is inserted through the alined bores in the offset feet 25, 26 its head confronting the offset foot portion 26 and its threaded end projecting beyond the offset 25. A coiled spring 29 encircles the projecting end of the shank between washers 30 engaging respectively the offset foot 25 and the inner face of a wing nut 31 threading on the outer extremity of the projecting shank of bolt 28.

With the hinging link 21 in its normal dead center drum clamping position shown in Figures 1 and 2, the wing nut 31 is turned up on the shank to tension spring 29 and give the desired frictional braking drag on the drum 7. Upward movement of the quick

release rod 23 does not change the adjustment which will be again in force when the rod is brought back to swing the eccentrically mounted link 21 back again to its original dead center position. Release of clamping pressure through up swinging of the rod 23 permits the warp beam to be turned back by hand when necessary to repair a break or defect in the weave, without working against the warp tensioning drag of the band brake.

In order that the band brake may function to produce warp tensioning frictional drag on the drum, it must be held against rotation with the drum. At the same time in order that the uniform frictional drag provided by the determinately fixed clamping adjustment of the rigid arcuate band sections may be maintained when through "out of round" or bent condition of the axial spindles 3, the band brake must move bodily with the beam and drum. This bodily movement is necessarily radial to the axis of the spindles, drum and beam and in accordance with my invention, the band brake is restrained from rotatory movement with the drum but at the same time is free to move bodily with the drum in a direction radial to its axis. This result is secured through cooperation of the radial extension 27 and a special stationary guide shown in Figures 1 and 4.

This guide comprises an end bracket 32 of metal extending in a vertical plane and rigidly bolted to the vertical face of the loom frame adjacent its base (Fig. 1) and positioned thereon to locate the outer end of an integral laterally offset plate 33 extended outwardly therefrom substantially at right angles at a point beneath and alined with the depending radial extension 27 and above its lower end. This offset plate 33 has its face turned relatively to that of bracket 32 to lie in a substantially horizontal plane and at a point in vertical alinement with the rigid extension 27 is provided with an elongated slot 34 therein conforming to but of slightly greater area than the cross section of said extension to permit free relative movement of said extension radially of the axis of the drum and beam, while at the same time, restraining by its ends, the extension 27 and its rigidly attached band brake, from rotation with the drum. The guide will be positioned vertically on the loom frame and the extension 27 will be of such length as to project its lower end a substantial distance below the guiding plate 33 to ensure proper restraint against rotation. The end faces of the plate 33 bordering the ends of the slot are substantially parallel to the end or edge faces of the extension 27 so that the latter, extending as it does radial to the axis of the drum, will be guided by the slot for bodily movement in directions radial to said axis. The rigid nature of the band brake sections and their fixed adjusted clamp-

ing pressure will ensure the application of constant and uniform frictional drag on the drum and tension on the warp threads under all conditions.

The peripheral band contacting face of the drum will have a smoothly finished surface and in order to maintain it smooth and to ensure an even frictional drag, it is preferably coated with graphite and is maintained properly lubricated or graphited by means of a lubricant reservoir or cup 35 which may be cast integral with a band section as shown, for example band section 12, and accessibly positioned at the top of the band brake to feed the lubricant or graphite to the drum by gravity, so that proper surfacing of the drum will be maintained. The bottom of the cup or reservoir 35 is, of course, ported into communication with the drum periphery through a feed passage extending downwardly through the band section and through its leather or other lining 13.

In order that my warp tensioning means may be available for application to warp beams not originally provided with friction drums, I have provided, as an attachment therefor, the separate drum and band brake shown more particularly in Figures 5 and 6 with structural details illustrated in Figures 7-9. And, since the attachable nature of this drum will require separation thereof from the warp beam proper when the latter is to be removed or applied, I have so constructed this drum attachment as to facilitate this operation. The band brake used thereon corresponds structurally with and is mounted and guided by a stationary frame attached bracket as in the form shown in Figures 1 and 4, and is therefore identified by corresponding reference numerals and will not be again described in detail.

The separate friction drum shown in Figures 5 and 6, comprises a hub portion 36 cupped to form an annular axial recess 37 and provided with an integral axial sleeve 38 outstanding from its opposite and outer side which is intended to slide over the axial spindle 3^a projecting from the standard head 2^a of the warp beam and is connected with said spindle by pawl and ratchet to rotate with the spindle and warp beam. The inner face of the drum outwardly of the recessed hub is in the form of a flat annular plate 40 extending in parallel with the outer face of the standard beam head 2^a and outwardly at its outer edge to form the circular rim 41 providing the drum periphery, preferably having bordering flanges 42 between which the band brake heretofore described is seated.

A ratchet wheel 43 is keyed or otherwise fixed to the beam spindle 3^a outwardly of the beam head 2^a, the diameter of this ratchet wheel being less than of the annular recess 37.

of the cupped hub so that the latter may be slid over the spindle to enclose the ratchet wheel therewithin.

One or more studs 44 as shown, for example two in diametrically opposed relation, extend through the cupped hub 36 from its outer face to which they are held by nuts 45. On the inner ends of these studs within the recess 37 and outwardly of the periphery 10 of the ratchet wheel 43, are journaled the hubs 46 of pawls 47 whose toothed ends 48 are normally urged into engagement with the teeth of the ratchet wheel by springs 49 having intermediate coils encircling the 15 studs and opposite ends engaging the inner faces of the cupped hub and overlying and tensioned against the outer edges of the pawls 47 as shown in Figures 7 and 8.

These pawls serve to normally connect the 20 drum with the ratchet wheel 43 for rotation therewith and with the spindle 3^a and warp beam head 2^a in warp letting off direction but permit the warp beam to be reversely turned by hand when it is necessary to repair the 25 weave. On such event the quick release bar 23 of the bandbrake is optionally operated to release the frictional drag of the band brake on the drum.

Since the pawls 47 are normally inturned 30 by their springs 49, it is necessary to swing them outwardly when the drums are being mounted on the spindles, and it is a convenience to swing them outwardly by means operative from the outer face of the drum hub 36 under such conditions and when the warp beam and its head are removed for replenishing the warp.

Accordingly the hubs 46 of the pawls 47 are provided with rearwardly extending 40 heels 50, and short spindles 51 extend through the outer face of the hub adjacent the studs and are provided with crank fingers 52 on their inner ends overlying the heels 50 of the pawls. Rock arms 53 (Fig. 5) are secured to 45 the outer ends of these spindles at the outer face of the hub 36 and may be swung by hand to cause the fingers 52 to press the pawl heels 50 inwardly, lifting the pawls from engagement with the ratchet wheel. Preferably, in 50 order to retain the pawls so outswung against the tension of their springs, the outer ends of the spindles are threaded at 51^a (Fig. 9) to screw into the hub 36 and the rock arms 53 are fixed to the outer extremities of the 55 spindles, outwardly of the hubs as by collars as shown in Figure 9. Thus the pawls may be retracted from the outer sides of the hubs and greatly facilitate the mounting of the hubs on the warp beam spindles.

60 The illustrated physical embodiment of the invention as described herein, represents, it is true, the invention in preferred form but is intended as illustrative rather than restrictive of the invention, whose physical form 65 may be modified in accordance with differ-

ent conditions of manufacture and use in consonance with the spirit of the invention and the scope of the appended claims.

And while the invention is conceived for and is of peculiar utility when applied to 70 and functioning in connection with the warp beam of the loom, it may, from the aspect of its physical structure, be suitable for use in connection with the warp beam in the slashing room or in connection with 75 similar rolls or beams requiring frictional drag inducing tension thereon.

What I claim is:—

1. In a loom, a warp beam having axial spindles journaled in the loom frame, a co- 80 axial friction drum fixed to and rotating with a spindle, a band brake enclosing and engaging said drum with frictional braking pressure and having a rigid extension projecting outwardly therefrom substantially 85 radial to the axis of the drum and warp beam, with a stationary guide cooperating with said extension to restrain said band brake from rotatory movement with said drum and coincidently effective to permit said band brake bodily to move with said drum in a direction substantially radial to the axis of the drum and warp beam, said band brake comprising complemental rigid arcuate sections hingedly connected at one of their 90 confronting ends and adjustably connected at their opposite confronting ends selectively to vary the frictional drag of said sections on the drum, said hingedly connected ends being interconnected by a hinging link having one end carried by a manually oscillatable eccentric movable from a fixed position of band and drum frictional clamping engagement to a band loosened friction-releasing position permitting friction free rewinding 100 of the warp beam, one of said band sections having the aforesaid rigid extension integral therewith and projecting outwardly therefrom at its said adjustably connected end, and a lubricant reservoir carried by one 105 of said band sections ported into communication with the drum contacting face of said band section.

2. In a loom, a warp beam having axial spindles journaled on the loom frame, a 115 ratchet wheel fixed to and concentric with a spindle outwardly of the warp beam, a friction drum rotatively mounted on said spindle in concentric relation to said beam having an axial recess in its inner face to receive the ratchet wheel therewithin and carrying on its inner face within said recess a pawl positioned to engage said ratchet wheel and normally held in engagement therewith to couple the drum thereto for rotation with said ratchet, spindle and warp beam in warp letting off direction and to permit rotation of the warp beam, spindle and ratchet wheel relatively to and independently of the drum in the reverse direction, 125 130

means manually operable from the outer face of the drum for moving said pawl to inoperative relation to the ratchet wheel, a band brake shaped to and embracing said drum with frictional braking pressure having a rigid extension projecting therefrom substantially radial to said spindle and warp beam axis, and a slotted guide fixedly carried by the loom frame and cooperating with said extension to restrain said band brake from rotation with said drum while coincidentally permitting bodily movement of said band brake with the drum and warp beam in a direction substantially radial to the axis of the warp beam.

3. In tensioning means, a pair of band brake sections, heads on each of the sections being in confronting relationship, one of the heads having a passageway and a transverse bore, a plug turnable in the bore, a link connected with one of the heads and connected off center with the plug, and a rod carried by the plug and occupying the passageway for turning the plug and thereby 25 tightening or loosening the link.

4. In a loom, a warp beam having axial spindles to be journaled on a loom frame, a ratchet wheel fixed on the spindle, a brake drum turnable on the spindle, being cupped 30 to form a recess for receiving the ratchet wheel and to provide a hub, a spring pressed pawl situated in the recess to engage the ratchet wheel and having a heel, a pivotal mounting for the pawl, a crank finger 35 in position against the heel, a threaded spindle carrying said finger and being screwed through the hub, and means outside of the hub to turn the spindle.
